UNITED STATES PATENT OFFICE.

BRUA C. KEEFER, JR., AND EUGENE W. GALETTI, OF WILLIAMSPORT, PENNSYLVANIA, ASSIGNORS TO BRUA C. KEEFER MANUFACTURING COMPANY, OF WILLIAMSPORT, PENNSYLVANIA, A CORPORATION OF PENNSYLVANIA.

TUNING DEVICE.

Application filed May 29, 1923. Serial No. 642,279.

To all whom it may concern:

Be it known that BRUA C. KEEFER, Jr., and EUGENE W. GALETTI, citizens of the United States, residing at Williamsport, county of Lycoming, State of Pennsylvania, have invented an Improvement in Tuning Devices, of which the following description, in connection with the accompanying drawings, is a specification, like characters on the drawings representing like parts.

This invention relates to musical wind instruments and has reference particularly to tuning devices for slide trombones and like instruments.

15 The invention aims to provide for easy and convenient assembling and manipulation of the instrument and the tuning device, which may be incorporated in existing types of instruments with slight changes, 20 whereby to facilitate accurate adjustments and hold the movable parts of the instrument in tuned relation.

Other objects and advantages of our invention will appear in the following description of the illustrative embodiment shown in the drawings, wherein:

25 Figure 1 is a side elevation of a trombone embodying one form of our improved tuning device;

30 Fig. 2 is an enlarged fragmentary view of the form of improved tuning device shown in Fig. 1;

Fig. 3 is a sectional view taken on the line 3—3 of Fig. 2; and

35 Fig. 4 is a sectional view taken on the line 4—4 of Fig. 2.

Referring to the drawings, we have shown a trombone of the well known type having a bell 1 and the usual U-shaped slide 2 carrying the tuning device 3 which is telescopically mounted on and forms a rearward extension of said slide, whereby the proper intonation may be obtained. The slide 2, together with the tuning device, are removable from the long tube 4 (see Fig. 2) and mouth tube 5 of the instrument.

In the form of instrument shown, the tube 5 for the mouth piece is secured to the long tube 4 which leads to the bell by means 50 of a cross brace 6 to prevent the mouth piece from moving with the slide.

The bell and associated flared tube portion of the instrument may be continuous around the first U bend 7 and preferably

has cross braces 8 at convenient intervals to 55 brace this portion to the long tube 4. If desired, the long tube 4, which telescopes in the top leg of the slide, as seen in Fig. 1, may be telescoped over the end of the bell tube attached thereto by means of a suitable 60 coupling 9 so as to facilitate removal of the slide together with the mouth piece, thereby permitting compact storage in an instrument case.

In the form of the invention illustrated, 65 our improved tuning device 3, is telescopically mounted on the rear ends of the legs of the slide 2 (Figs. 1 and 2), and preferably comprises two short sections of tubing 10 connected together rigidly by a cross 70 brace 11. The rear ends of the tubing sections engage beads 12 on the long tube 4 and mouth tube 5, respectively, to limit the movement of the slide.

In order to change from high to low pitch 75 and to adjust the intonation of the instrument as desired, the tuning device 3 may be moved toward or away from the U bend of the slide 2, thereby changing the effective 80 length of the whole system of tubing. To accomplish accurate adjustments of the tuning device 3 we have provided a cross brace 13 on the legs of the slide 2, and an adjusting screw 14 is connected to this cross brace and to the brace 11, passing through sleeves 85 15 and 15^a secured in said cross braces. The screw has a knurled enlarged portion 16 between the braces, for manipulation by the finger or thumb of the user. The shoulder at the left end of the knurled portion (Fig. 90 2) abuts against the end of the sleeve 15^a in the brace 11 and the shoulder 17 at the right end forms a limiting stop for the device when it is moved to the right. The left end of the screw is swivelled in the cross brace 11; that is, it is freely rotatable in the sleeve or bearing 15^a and has a retaining collar 18 95 removably secured on its end in engagement with the left end of the bearing sleeve 15^a. Screw threads 19 are cut from the shoulder 100 17 to the right end of the screw and are threaded through the sleeve 15 in the cross brace 13. A threaded collar 20 forming a limiting stop for the device is preferably 105 secured on the end of the screw by means of a set screw or the like.

Now, if it is desired to change the adjustment of the tuning slide 3 the operator will

turn the screw 14 in the proper direction, by the knurled portion, and thereby adjust the tuning device to the right or left to shorten or lengthen the effective length of the slide.

5 After proper tuning is effected, the screw will hold the tuning device on the slide in its adjusted position. It will be observed that the outer limit of the adjustments is governed by the position of the collar 20 which 10 is adjustable on the screw. Also when the tuning device is set in position for proper intonation the collar 20 may be screwed into engagement with the sleeve 15 and then secured to the screw (see the dotted position 15 in Fig. 2) thereby enabling the user to reset the tuning device quickly in case of accidental displacement.

Further, it will be noted that the tuning device 3 may be removed from the legs of 20 the slide 2 without disturbing the adjustment or setting of the screw, by simply removing the collar 18 from the left end of the screw and then sliding it off. Thus, no readjustment of the tuning device is required upon re-assembling.

Obviously our invention is susceptible of various changes.

What we claim and desire to secure by Letters Patent is:

30 1. In a tuning device for slide trombones and the like, the combination of a tuning member mounted on the ends of the sliding tubes thereof and slidable therewith, a cross brace on the tuning member having a bearing sleeve therein, a cross brace on the sliding tubes having a threaded sleeve therein, an adjusting screw swivelly mounted and removably secured in said bearing sleeve and threaded through said threaded sleeve, manipulating means on the screw between 35 said cross braces and stops for limiting the movement of said tuning member in both directions.

40 2. In a tuning device for slide trombones

and the like, the combination of a tuning 45 member mounted on the ends of the sliding tubes thereof and slidable therewith, a cross brace on the tuning member having a bearing sleeve therein, a cross brace on the sliding tubes having a threaded sleeve therein, 50 an adjusting screw swivelly mounted and removably secured in said bearing sleeve and threaded through said threaded sleeve, manipulating means on the screw between 55 said cross braces, said manipulating means forming a limiting stop for the tuning member in one direction and adjustable stop means secured on the screw to limit movement of the tuning member in the other direction. 60

3. A tuning device for slide trombones and the like, comprising, in combination, a tuning member mounted on the ends of the sliding tubes thereof, a cross brace on said tuning member, a cross brace on said sliding tubes, an adjusting screw swivelly mounted 65 in one of said cross braces and threaded through and projecting beyond the other cross brace, a removable retaining means on the swivelled end of said screw and manipulating means on said screw between 70 said cross braces.

4. A tuning device for slide trombones and the like, comprising, in combination, a tuning member telescopically mounted on 75 the ends of the sliding tubes thereof, a cross brace on said sliding tubes, a cross brace on said tuning member, adjusting means for the tuning member swivelly connected to one of said cross braces and threaded 80 through and projecting beyond the other cross brace, and manipulating means on said adjusting means between said cross braces.

In testimony whereof, we have signed our 85 names to this specification.

BRUA C. KEEFER, JR.
EUGENE W. GALETTI.
